UNITED STATES PATENT OFFICE.

KARL KÜPFMÜLLER, OF BERLIN-FRIEDENAU, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

DISTORTION COMPENSATOR.

Application filed February 1, 1924, Serial No. 689,972, and in Germany October 5, 1923; November 27, 1923.

This invention relates to improvements in transmission systems with loaded lines for the transmission of signals over long distances.

5 It is well known that in the telephonic transmission over long loaded cables, a distortion of the speech currents takes place due to transient phenomena. This distortion determines the transmission range of 10 the lines, which depends on the value of the so-called cut-off frequency ω_0 of the loaded line,

$$\omega_0 = \frac{2}{\sqrt{L_0 C_0}} \quad (1)$$

15 wherein L_0 and C_0 are the inductance and the capacity of the coil sections. In order to counteract the detrimental transient effects which occur when handling telephone 20 service over very long distances, it is necessary to keep the cut-off frequency higher than is otherwise used, for instance by reducing the inductance of the coil, L_0 . This involves, however, an increase in attenuation 25 and thus an uneconomical utilization of the circuits.

The object of the present invention is a balancing method for correcting the distortion of the speech currents caused by transient 30 phenomena. The application of this method thus renders it possible to carry on a conversation successfully over any distance by lines loaded in the known manner from economical points of view.

35 Figs. 1 to 3, 6 and 7 are curves used in explaining the invention. Fig. 4 shows a speech transmission system designed in accordance with the invention. Fig. 5 represents a section of the network used in Fig. 4.

40 In order to explain the improved process, it is necessary to consider first of all the cause of this distortion. It is known that alternating currents, along smooth lines, are transmitted undistorted particularly at 45 higher frequencies. The alternating current of any frequency ω reaches the distant end of the line, having the length l , the inductance L and the capacity C per unit length in accordance with the known propagation 50 time

$$t_0 = l \sqrt{LC} \quad (2)$$

Long lines being assumed, the initial alternating voltage $V_0 \sin \omega t$ produces at the

distance x from the sending end, the voltage 55

$$V_x = V_0 e^{-\beta x} \sin (\omega t - \alpha x) \quad (3)$$

wherein α indicates the angle, and β the attenuation. At higher frequencies we have

$$\alpha = \omega \sqrt{LC} \quad (4)$$

with sufficient accuracy, α thus being proportional to frequency and β constant, particularly if the effect of the dielectric losses is not taken into account. Since according to 65 Fourier's theorem all transient phenomena in the line are determined by the effect of frequency variation on the physical quantities voltage or current, in steady-state condition, it may be concluded: if an alternating voltage V_0 is applied to a network and the voltage V_x between any two points of the network in the steady state is given by

$$V_x = V_0 e^{-b} \sin (\omega t - a) \quad (5)$$

in which "b" is constant and "a" proportional to the frequency, the alternating currents will be transmitted with a certain lag of time, but without distortion. Since the lag is equal at all frequencies, it would be without influence on the conversation across such a network; it produces only a delay in the arrival of the words heard in the receiver. Examining to what extent the relation (5) is fulfilled in a long loaded line, we find that the quantity "a" increases in a higher rate than frequency. According to the theory of wave filters which, as is well known, may be applied with great accuracy to loaded lines, this quantity is given 90 for a line of the length l by

$$a_0 = 2 \frac{l}{s} \arcsin \frac{\omega}{\omega_0} \quad (6)$$

where s is the distance between two coils and l the length of the line. Hence we obtain for low frequencies approximately the equation (4) in the form

$$a = 2 \frac{l}{s} \frac{\omega}{\omega_0} \quad (7)$$

as we may put the sine equal to the angle. For higher frequencies "a" rises quickly, as is shown in Fig. 1.

The general attenuation curve results from the following. It is well known that repeaters are constructed so as to compensate the steady-state distortion of the alternating

2

currents caused by the electrical properties of the line, particularly within the range of the voice frequencies. In long loaded lines provided with repeaters, the quantity b 5 varies with frequency approximately as shown in Fig. 2. In the range ω_1 to ω_2 which includes the important voice frequencies, b remains to a large extent constant. Comparing various lengths, it will be seen 10 that the curves of the remaining attenuation differ essentially only in the slope above and below ω_1 and ω_2 . Practically, oscillations which lie considerably beyond this range are, however, not transmitted even in the case 15 of comparatively short line lengths. Thus the effect of frequency variation on the attenuation b proves to be no source of distortion for the voice currents in long lines. This distortion therefore is due to the difference of 20 the quantity a_0 , equation (6), from the values in the equations (4) and (7). In practice it has hitherto been attempted to avoid this distortion by increasing the value a_0 considerably. Closer examination will 25 show that in such a way the differences between the quantities given by the equations (6) and (7) are actually diminished.

The present invention relates to suitable means for making the difference $a_0 - a = \Delta$ 30 small within the important frequency range, that is, for supplementing a_0 in such a manner that the new phase angle increases in the ratio of frequency. In this way the condition attached to the equation (5) is fulfilled, 35 no matter to what extent the line is loaded, so that all oscillations of the voice currents arrive with the same lag. Said means may be inserted in the line at one or several points, for instance at the repeater stations. 40 From the equations (6) and (7) follows for the difference within the important frequency range by developing the terms into series

$$\Delta = \frac{l}{3s} \left(\frac{\omega}{\omega_0} \right)^3 \quad (8)$$

For a line having the cut-off frequency $\omega_0 = 18000$, the coil distance $s = 2$ km. and the length $l = 150$ km., this relation gives the 50 angle differences represented in Fig. 3. In the same figure a broken curve e. g. indicates those values up to which the angle differences Δ are supplemented according to this invention, so that the total phase angle increases 55 in the ratio of frequency.

Fig. 4 shows a part of the speech transmission system across a long loaded line according to the system of the invention. K_1 and K_2 represent two cable sections, each of 60 which connects two repeater stations. The repeaters of a four-wire system for instance are indicated by V . The device B represents the additional set to be connected with the line according to this invention. This device is to be considered as a recurrent net-

work of two sections, the single sections of which are shown in Fig. 5. The sections of said recurrent network are of the so-called lattice type. Two of the four bridge branches are provided with two equal chocking coils L , while the other two contain two equal condensers C . Such a network has the property that it uniformly allows all frequencies to pass, the network being assumed non-dissipative, and that its char- 75

acteristic impedance is equal to $\sqrt{\frac{L}{C}}$ inde- 80 pendent of frequency. The effect of frequency variation on the phase angle α between initial and end voltage may be represented by the function

$$\cos \alpha = \frac{1 - \omega^2 LC}{1 + \omega^2 LC} \quad (9)$$

which can easily be ascertained by the well known formulae of current distribution and the theory of the recurrent networks. This function is shown in Fig. 6. For low frequencies α is approximately proportional to 90 the frequency; then increases more slowly with the rising frequency and finally approaches the value 2π for very high frequencies.

It will thus be seen that the above 95 described recurrent network is not a wave filter, and just this property renders it particularly suitable for the purpose of phase supplementing.

Fig. 7 shows how the phase difference Δ of a loaded cable, 300 km. in length and of the cut-off frequency $\omega_0 = 16500$, is supplemented by inserting a 10-sections network of the above described type with the constant

$$\sqrt{LC} = \frac{1}{7000}$$

The characteristic impedance of the sup-

plementary network being equal to $\sqrt{\frac{L}{C}}$, it 110 may easily be adapted to the impedance of the loaded line. This impedance too is approximately non-inductive, as is well known, and varies with frequency according to the 115 relation

$$W = \frac{Z_0}{\sqrt{1 - (\frac{\omega}{\omega_0})^2}} \quad (10)$$

ω_0 is the cut-off frequency of the loaded line, 120 Z_0 the characteristic impedance of the equivalent smooth line. The root differing essentially from 1 only for comparatively large ω , the energy losses between supplementary network and line are negligible.

The supplementary network B may be placed either at the end of the whole transmission system or it may be distributed between the repeater stations. In general it 125 will be preferable to correct, in the manner 130

described, each repeater section by itself, as it increases approximately in the ratio of the quality of transmission is independent of the length of the communication without special provisions at the end station.

5. What I claim as my invention and desire to secure by Letters Patent is:

1. The combination in a wave transmission system of a loaded line for the transmission of signals over long distances, with a localized compensating network, which produces a phase displacement supplementary to that produced by the loaded line, so that the phase angle between the initial voltage and the terminal voltage increases substantially 15 in proportion to the frequency of the transmitted waves.

2. In combination in a transmission system with loaded lines for communication over long distances, recurrent networks of 20 the so-called lattice type, the sections of which consist of four bridge branches, two of said branches consisting of two equal choking coils, and the other two of two equal condensers, said networks supplementing the 25 phase angle between the initial and the end voltage in such a manner that said phase angle increases approximately in the ratio of frequency.

3. In combination in a transmission system with loaded lines for the transmission of signals over long distances, means to supplement the phase angle between the initial and the end voltage in such a manner that

it increases approximately in the ratio of frequency, said supplementing of the phase angle taking place at the repeater stations.

4. In combination in a transmission system with loaded lines for communication over long distances, recurrent networks, the sections of which consist of four branches, 40 two of said branches consisting of two equal choking coils and the other two of two equal condensers, said networks supplementing the phase angle between the initial and the end voltage in such a manner that said phase 45 angle increases approximately in the ratio of frequency, said supplementing of the phase angle taking place at the repeater stations.

5. In combination, a loaded line whose 50 plot of phase distortion in angular measure against frequency is principally concave upward from zero to the upper limiting frequency of the desired range, and a lattice type network whose corresponding plot is 55 concave downwardly, whereby the combination gives a plot which is approximately a straight line through the origin.

6. In combination, a loaded line having repeaters at appropriate intervals, and with 60 each repeater a lattice type network to compensate phase distortion on the corresponding section of the line.

In testimony whereof I affix my signature.

KARL KÜPFMÜLLER.
